DESIGN.

P. M. CAREY.

DOLL.

APPLICATION FILED JULY 24, 1919.

54,595.

Patented Mar. 9, 1920.

Inventor,

Patricia M. Carey;

By Raymond H. Hale,
Attorney.

UNITED STATES PATENT OFFICE.

PATRICIA M. CAREY, OF LOS ANGELES, CALIFORNIA, ASSIGNOR TO LESLIE C. Brintnall, OF LOS ANGELES, CALIFORNIA.

DESIGN FOR A DOLL.

54,595.

Specification for Design.

Patented Mar. 9, 1920.

Application filed July 24, 1919. Serial No. 313,112. Term of patent 7 years.

To all whom it may concern:

Be it known that I, PATRICIA M. CAREY, a citizen of the United States, residing at Los Angeles, in the county of Los Angeles and State of California, have invented a new, original, and ornamental Design for Dolls, of which the following is a specification, reference being had to the accompanying drawing, forming part hereof, in which—

The figure is a front elevation of a doll embodying the invention, the doll being shown in a sitting position.

I claim:

The ornamental design for a doll, as shown.

PATRICIA M. CAREY.

Witnesses:

LESLIE C. BRINTNALL,
HUGH S. HILL.
